UNITED STATES PATENT OFFICE.

DAVID L. BARNES, OF CHICAGO, ILLINOIS.

COUPLER-GAGE.

SPECIFICATION forming part of Letters Patent No. 450,947, dated April 21, 1891.

Application filed September 29, 1890. Serial No. 366,547. (No model.)

To all whom it may concern.

Be it known that I, DAVID L. BARNES, a citizen of the United States, residing at Chicago, Cook county, Illinois, have invented a new and useful Improvement in Coupler-Gages, of which the following is a specification.

As is well known to those conversant with this art, the master car-builders of the United States have agreed upon a certain standard form of vertical hook-coupler, requiring that a coupler to come up to such standard shall conform in shape to certain contour lines without reference to the manner of operating the rotating hook or other means of engagement between the couplers. The object of having such a standard is to obtain uniformity of construction and enable the cars of one road to couple with those of a different road, their couplers being similar in shape. The jaws of these couplers, however, gradually become so worn in use that they no longer conform to the desired lines. A certain amount of departure from such lines may be allowed without danger, but a point is finally reached at which the form of the jaws is so changed that the couplers will separate when subjected to a heavy strain.

Some means is necessary with which to measure the distance between the jaws to determine when such distance has become so great as to render any further use of the coupler unsafe. This means it is the object of my invention to provide, and such invention consists in the features and details of construction hereinafter described and claimed.

In the drawings, Figure 1 is a plan view of the contour lines of a coupler with my improved gage applied thereto, showing the coupler unworn; Fig. 2, a similar view showing the coupler so worn as to be unsafe for further use; and Figs. 3, 4, and 5, plan views of modified forms of gage.

A is the coupler; B B', the jaws thereof; C, the gage, and D D' the arms thereof.

The construction of the coupler, except as regards the outline or contour lines thereof, is no part of my invention. These contour lines are shown in the first two figures of the drawings, and with what has been said above explain themselves and require no further description.

The gage C is made of wood, iron, or other suitable material. It preferably comprises a box, which holds the arms, and an extension 55 or leg E. In the preferred form this leg is curved to fit the coupler, and is provided with projections e, adapted to contact with the surface of the coupler, as shown in Fig. 1.

The arms D D', when made as shown in 60 Figs. 1, 2, and 3, slide back and forth in the box C, and the gage should be so shaped that when applied to an unworn coupler the leg E will fit, as shown, to the outside of the jaw B', the arm D will abut against the jaw B, 65 and the arm D' against the jaw B', the two arms being then in line. When applied to a coupler so worn as to be unsafe, the arms will assume the position shown in Fig. 2, with the arms pushed forward until they touch the 70 jaws. An indicator-line is preferably drawn or a mark made upon one or both of the arms, or upon one of the arms and the box, as shown, and when the arms, in order to contact with the jaws, have to be moved until this line is 75 reached or passed the coupler is unsafe for use. The position of this indicator-mark will of course vary according to the standard to which the coupler is required to conform; and, if desired, more than one mark may be used, 80 forming, as it were, a scale by means whereof the relative travel of the arms and the amount of wear of the coupler may be determined with accuracy.

In Figs. 1 and 2 the arms shown are adapted 85 to be moved by hand, being held by friction with the box.

In Fig. 3 set-screws F F are provided to move the arms, the screws working through shoulders on the box and arms.

In Fig. 4 one arm slides in the box and the other is pivoted upon the sliding arm, being carried forward with it.

In Fig. 5 one arm slides and the other is pivoted to the box.

When in any of these last three devices the arms, in order to contact with the jaws, have to be moved until the indicator-lines coincide, the coupler is unsafe. These are shown as various forms of my device, but not as the 100 only ones, nor as a limitation to any or all of them, my invention consisting, broadly, in providing a gage for measuring vertical hook-couplers, and any other form may be em-

ployed that will accomplish the desired result.

I claim—

1. A coupler-gage comprising a leg adapted to contact with the exterior of one of the coupler-jaws, and movable arms adapted to contact with the interior of the jaws respectively, substantially as described. 5

2. A coupler-gage comprising a box, a leg adapted to fit upon the exterior of the jaw, and movable arms adapted to contact with the interior of the jaws, respectively, substantially as described. 10

3. A coupler-gage comprising a box, a leg, an arm sliding in the box, and an arm pivoted to the box or to the arm, substantially as described. 15

4. A coupler-gage conforming, when its parts are in their normal position, to the contour lines of a coupler and adapted to be adjusted to indicate the degree of departure of 20

the coupler from such lines, substantially as described.

5. A coupler-gage comprising a fixed member contacting with the exterior of the coupler-jaw and one or more movable members contacting with the interior of the coupler-jaws to determine the amount of wear of the coupler and its conformity or non-conformity to a desired standard, substantially as described. 25

6. A coupler-gage to determine the condition of a vertical-plane coupler, which is aligned by the knuckle of the coupler and is provided with one or more adjustable members for determining the relative position of the parts of the coupler, substantially as described. 30

DAVID L. BARNES.
